United States Patent Office

Des. 228,449
Patented Sept. 25, 1973

228,449

MOTEL BUILDING

Howard L. Schwartz, Miami Beach, Fla., assignor to United Inns Mfg. Corp., Kansas City, Mo.

Filed Apr. 24, 1972, Ser. No. 247,227

Term of patent 14 years

Int. Cl. D25—03

U.S. Cl. D13—1 B

Fig. 1.

Fig. 3.

FIG. 1 is a perspective view of a motel building embodying my design.

FIG. 2 is a plan view thereof.

FIG. 3 is a side elevational view thereof.

FIG. 4 is an end elevational view thereof.

FIG. 5 is an enlarged fragmentary sectional view showing a projection and roof contour at the sides thereof.

FIG. 6 is an enlarged fragmentary sectional view showing a projection and roof contour at the ends thereof.

I claim:

The ornamental design for the motel building, as shown and described.
